W. H. Halloway, Design for the Base of a Stove; Des 978 to L. M. & W. H. Halloway, Warren & Morrison, of Troy, N.Y.

Patented Jan'y 12. 1855.

Des. 978

David Hathaway of Troy N.Y.
Assignor to Fuller, Warren & Morrison of same place.
Letters Patent No. 978. Dated Jan 12, 1858.

The schedule referred to in these Letters Patent and making part of the same.

To all whom it may concern:

Be it known that I, David Hathaway of the city of Troy, in the County of Rensselaer, and State of New York, have invented or produced a new and original Design for the Base of a Cottage Parlor Stove; and I do hereby declare that the following is a full and exact description of the same, reference being had to the annexed photograph, - making a part of this Specification.

My ornamental design for the base, or bottom plate, of a stove, consists of the ornamental molding, a, around the oval flange which receives the upright plates or casing of the stove, - the large compound rosetts b, at each of the four corners of the plate, - the ornamental scroll, c, in the middle of the front part of the plate
, and the ornamental border moldings, d, joining the scroll and rosetts, - all shaped and arranged as shown in the annexed photographic drawing. -

What I claim as my invention or production and desire to secure by Letters Patent, is, the ornamental design above described and shown in the annexed photographic drawing for the base of Excl a stove.
